SKIRT MARKER

Herbert G. Booth, Purchase, N. Y., assignor to
 David Traum Company, Incorporated, a corpora-
 tion of New York

Application July 3, 1948, Serial No. 37,022

4 Claims. (Cl. 33—9)

1

This invention relates to marking devices and more particularly to a garment hem marker.

It is among the objects of the invention to provide a skirt marking assembly that is neat, compact and rugged in construction having but few inexpensive parts none of which is likely to get out of order and which lends itself readily to quantity production, that may readily be used even by an unskilled housewife to mark a hem without danger of injury to the dress and without the use of crayon, chalk or powder and by use of which both the desired length of the dress and the width of the hem can be marked in but a single operation.

According to the invention these objects are accomplished by the arrangement and combination of elements hereinafter described and particularly recited in the claims.

In the accompanying drawings in which are shown one or more of various possible embodiments of the several features of the invention:

Fig. 1 is a perspective view of the skirt marking assembly,

Fig. 2 is a longitudinal sectional view on a larger scale taken along line 2—2 of Fig. 1 showing one of the clamping jaws in dot and dash lines in open position,

Fig. 3 is a transverse sectional view on a larger scale, taken along line 3—3 of Fig. 2,

Fig. 4 is a view similar to Fig. 3 taken along line 4—4 of Fig. 2,

Fig. 5 is a view similar to Fig. 3 taken along line 5—5 of Fig. 1, and

Fig. 6 is a fragmentary perspective view of a portion of one of the clamping jaws.

Referring now to the drawings the skirt marking assembly as shown in Fig. 1 comprises an upright standard or support 11, desirably a yardstick or graduated bar, rectangular in cross-section, of width greater than its thickness and having appropriate markings thereon, a base 12 supporting said graduated bar in upright position and a marking device 13 slidably mounted on said bar.

The marking device 13 which is desirably a single sheet metal stamping, although it could be of wood or plastic, comprises a slide member 14 having a cross piece 17 of channel formation at the lower end thereof with its rearwardly bent lateral flanges 16 straddling yard stick 11, that serves as a track along which member 14 may be slid to any position of adjustment.

In order to retain slide member 14 in any desired position of adjustment on yardstick 11, rearwardly extending transversely aligned ears

2

18 and 19 are provided, preferably integral with the respective flanges 16 near the lower ends of the latter, lying in the same plane therewith.

Ears 18 and 19 are provided with aligned openings 21 and 22 therethrough respectively, through which extends a carriage bolt 23, opening 21 being square as shown to conform to the square portion 24 of bolt 23 near the head 25 thereof, thereby to prevent the bolt from turning. A wing nut 27 is provided on the threaded end 28 of carriage bolt 23 extending through opening 22 beyond ear 19, which wing nut when tightened will move flanges 16 and ears 18 and 19 towards each other, tightly to grip the sides 29 of the yardstick, thereby holding the slide member 14 in place. As only the sides of the yardstick are gripped there will be no danger of the markings on the face thereof being scratched or obliterated which would make reading such markings difficult.

Slide member 14 is provided with a jaw configuration or clamping jaw 31 preferably integral with and extending longitudinally upward from the cross piece 17. Said jaw configuration, as is clearly shown in Figs. 2, 3 and 6, preferably has a convex face and since it is of sheet metal has a concave under surface. It is narrower than the yardstick, is several inches long and is provided with a plurality of spaced, transverse depressions 33 across its convex face spaced along the length thereof, one near the upper and one near the lower end thereof, and has lateral borders 43.

The lower end of cross piece 17 has a pair of ears 35 struck out therefrom and transversely aligned thereon by means of which a clamp arm 36 is pivotally connected to the slide member 14. Arm 36 has on each side of its substantially rectangular lower end 41, a rearwardly extending ear 37, which ears 37 straddle ears 35, and a pivot pin 38, headed at each end, extends through said ears 35 and 37 to form the pivotal connection, end 41 being provided with longitudinal strengthening ribs 46 to prevent bending thereof.

Arm 36 has a jaw configuration complementary to that of the slide member upon which it is mounted. Preferably said arm has a concave under face along the major part of the length thereof with lateral flanges 43 which lie in a plane parallel to rectangular end 41 and forms clamping jaw 36' which corresponds to and contacts with the convexity of the clamping jaw 31 to clamp an interposed skirt fabric against the convex face of the latter.

Pairs of transversely aligned notches 44 are provided in the lateral flanges 43 of the clamping jaw portion 36' of arm 36, as well as in the slide

edges 44' thereof, which are spaced along the length thereof. The notches are so positioned, that when the arm 36 is moved to closed position against slide member 31 in the manner herein-after described, a pair of notches in jaw 36' will register with each transverse depression in jaw 31, the notches and depression being of such depth that a transverse passageway 45 will be formed at each marking place as is clearly shown in Fig. 2.

Base 12 which supports the graduated bar and marking device 13 thereon comprises a pair of identical substantially U-shaped brackets 47 each of the cross pieces 48 of which has a recessed portion 49 with an opening 51 in the center thereof.

To assemble the base to the graduated bar, the brackets are positioned so that the recessed portions 49 thereof respectively are against the faces of the bar at the lower end thereof, and a bolt 52 is passed through openings 51 in the recessed portions and an opening 53 in the bar. By means of a nut 54 threaded on the end of the bolt the recessed portion of each of the brackets is securely clamped against the associated face of the bar securely to hold the base in place, with the outstretched legs 55 of the brackets providing a firm and stable support.

The main purpose and use of the assembly is to mark around the hem of a skirt while on the person, uniform distances from the floor, so that the skirt may be of the desired length and also to mark the lower part of the skirt so that the hem will be the same width all around.

To this end the movable member 14 is adjusted along graduated bar 11 so that a transverse depression 33, preferably the uppermost depression, is aligned with a scale marking on the bar indicating the number of inches it is desired that the bottom of the skirt be spaced from the floor. As the curved jaw 31 is narrower in width than the graduated bar, the scale markings thereof will be clearly visible.

The wearer of the skirt stands adjacent the upright marking device with the bottom of the skirt positioned between the open clamping jaws 31 and 36'.

The clamping jaw 36' is then moved to closed position, thereby clamping the skirt therebetween as is shown in Figs. 1, 2 and 3. The person doing the marking then need merely insert a conventional pin 40 through the passageway 45 formed by notch 44' and the associated transverse depression 33 at the selected height above the floor. The pin will readily pass through and make but two small holes in the fabric clamped between the curved jaws 31, 36', as shown in Fig. 3.

Without releasing the clamp, a second pin may then be inserted in a passageway 45 below the first to mark the width of the hem desired so that the accuracy in positioning and spacing of the two pins is assured. As the openings are illustratively one inch apart it is apparent that a hem of one, two or three inches may be marked. It is of course to be understood that the openings could be other distances apart and more or less could be provided.

The procedure above described is repeated at intervals along the circumference of the skirt and when this is completed the skirt has been marked both for length and for width of the hem with a double row of pins around the skirt each row uniformly distant from the floor and effected in an accurate and speedy manner.

It will be observed that after the proper dis-

tance is located on the skirt and the jaws are clamped together the fabric is firmly held at the proper marking point and it is immaterial whether the device is positioned on the floor or whether it is lifted to more readily effect the pinning or marking, for in either event the fabric remains tightly clamped against shifting until both pins have been introduced.

As the pivotal connection between slide member 14 and arm 36 is near the lower end of the device, it is apparent that the device can be used to mark even a dress that almost touches the floor.

As many changes could be made in the above construction, and many apparently widely different embodiments of this invention could be made without departing from the scope of the claims, it is intended that all matter contained in the above description or shown in the accompanying drawings shall be interpreted as illustrative and not in a limiting sense.

Having thus described my invention what I claim as new and desire to secure by Letters Patent of the United States is:

1. A skirt marking assembly comprising a standard, a slide member on said standard consisting of a single metal stamping, the lower part of said stamping comprising means straddling said standard and serving frictionally to retain said slide member in adjusted position upon said standard, the upper part of said slide member consisting of a jaw configuration several inches in length, having parallel lateral borders engaging the face of said standard, an arm pivotally mounted upon said slide member near the lower end of the latter, a jaw configuration on said arm complementary to and of the length of that of said slide member, the jaw configuration on said slide member having a plurality of longitudinally spaced transverse depressions therein including one near the upper and one near the lower end thereof and the jaw configuration on said arm having a plurality of longitudinally spaced transversely aligned notches in the side edges thereof in registry with the respective depressions when said arm is pivoted to upright position against said slide member, thereby to form a corresponding plurality of transverse passageways, whereby a pin may be inserted horizontally through the uppermost of said passageways into the fabric of a skirt clamped between said jaw configurations and while the jaws are still closed, a second pin may be inserted through one of the other passageways determined by said jaws, thereby to define with accuracy respectively the length of the skirt and the width of its hem.

2. The skirt marker recited in claim 1, in which the standard is a graduated bar rectangular in cross-section, of face width greater than its thickness, in which the straddling means at the lower end of the slide member is of channel formation, in which the jaw configuration of the slide member has a convex face narrower than said standard with the edges thereof forming the borders in engagement with the face of said standard and in which the pivoted jaw member has a concave under face engaging substantially the entire length of said convex face of the slide member.

3. The combination recited in claim 1, in which the standard is in the form of a graduated bar, rectangular in cross-section, of face width greater than its thickness, the straddling means at the lower part of the slide member is of channel formation and extends across the face of the stand-

ard, in which ears protrude rearward of the sides of the standard and substantially in the planes of the respective lateral edges of the graduated bar, and in which a transverse bolt keyed in one of said ears extends through the other ear and has a wing nut on the free end thereof frictionally to clamp the channel in adjusted position upon the standard.

4. As an article of manufacture, a skirt marking assembly adapted for installation in any of a plurality of adjusted positions upon a standard that includes an upright graduated bar rectangular in cross-section, said article comprising a sheet metal slide member channel shaped at its lower portion to present a face and rearwardly extending sides, ears in the planes of the respective sides for accommodating a cross bolt, a jaw conformation integral with and extending upward from said channel shaped portion, of width narrower than said channel, trough shaped in cross section and presenting a convex outer face several inches in length and having a plurality of transverse depressions, one near the upper and one near the lower end thereof, a complementary sheet metal jaw member pivoted near its lower end to said channel shaped portion and of length, width and conformation complementary to that of said convex face on the slide member, said jaw member including a concave under surface adapted in closed position to engage the entire length of and to extend about the convexity of said jaw conformation, and having notches in its side edges in registry with the respective depres-

5
sions in the convex member to determine transverse passageways in closed position thereof.
